(57) **CLAIM**

I claim the ornamental design for a pole bracket for a banner or flag, as shown and described.

DESCRIPTION

FIG. 1, is a front perspective view of a pole bracket showing my new design;

FIG. 2 is a front elevational view thereof;

FIG. 3 is a left side elevational view thereof;

FIG. 4 is a top view thereof;

FIG. 5 is a bottom view thereof; and,

FIG. 6 is a back elevational view thereof.

In FIG. 1 the location for a hole for a banner tie is shown in dotted broken line and a partial segment of a banner and flag pole for the bracket is shown in a dashed broken line and are included for illustration purposes only and form no part of the claimed design.
